UNITED STATES PATENT OFFICE.

GEORGE E. THACKRAY, OF WESTMONT BOROUGH, PENNSYLVANIA.

MAKING INGOTS.

1,409,040.

Specification of Letters Patent. Patented Mar. 7, 1922.

Application filed April 12, 1921. Serial No. 460,673.

To all whom it may concern:

Be it known that I, GEORGE E. THACKRAY, a citizen of the United States, and a resident of the borough of Westmont, county of Cambria, and State of Pennsylvania, have invented certain new and useful Improvements in Making Ingots; and I do hereby declare the following to be a full, clear, and exact description of the invention, such as will enable others skilled in the art to which it appertains to make and use the same.

My invention relates to improvements in making ingots with special reference to producing an ingot free from fins or projections on its lower portion in order to prevent shrinkage strains and cracks while cooling, and while this is adapted to various forms of ingots, it is especially useful with ingots of the type having their larger ends upward, which are thus made in order to concentrate the piping or shrinkage cavities in the upper portion within the refractory material or lining of the sink-head top which may be used in this connection. Ingots, and particularly those of the big-end-up type, should not have fins projecting from their lower end between the stool and the ingot mold, caused by molten ingot metal penetrating the joint or crack at this location, for the reason that on account of the taper of the mold the ingot would be held somewhat thereby, and as it cools the fins would hold it and in a measure prevent its contraction when cooling, thus producing shrinkage cracks in and extending inwardly from the surface, which makes defects in the product. If fins are thus formed it makes it difficult to remove the ingot from the mold, as it has to be withdrawn from the larger end, and the fin on the smaller end would prevent this. By means of my improved manner of preparing ingot molds and casting ingots therein I obviate these difficulties.

Trouble has always been had due to the inclusion within the ingot of small or large particles of foreign or refractory material, such as slurry, clay wash, loam, parts of the sink-head top lining, or other material which has heretofore been used to seal the joint between the ingot mold and the stool upon which it rests in order to prevent entrance therein of molten steel. It has been

the ordinary practice to pour slurry or clay wash formed of loam, clay, etc., of a powdered character mixed with water to form a grout of creamy consistency into the ingot mold after it is seated on the stool with the idea of sealing the crack or joint between the ingot mold and the stool, and the water was evaporated therefrom by the heat of the mold and stool due to previous use. This, however, leaves irregular and loose lumps of refractory material in the bottom of the mold, and when steel or other metal is poured therein this refractory material may be floated upwardly to various extents, and if retained in the ingot causes defects due to inclusions thereof.

Although my means of sealing bottoms of ingot molds is particularly applicable and useful in connection with making ingots with large ends upward, it is also applicable to the ordinary types with large ends down, and when used under such conditions will provide an ingot with a more perfect bottom and which will consequently handle better and roll better without forming laps or seams and one that will enter the roll passes more readily than an ingot having a bottom fin.

In order to practice my invention I provide a metal stool having a pad projecting upwardly from the upper surface thereof, which pad is a little smaller than the inside of the bottom of the ingot mold and conforms to the general shape thereof, leaving a groove or space between said pad and the bottom of the inside of the ingot mold, which groove may be taper or parallel or of any other form desired.

Instead of employing the usual mud or slurry to seal the joint which causes inclusions in the ingot as before stated, I provide a gasket which may be made of one continuous form or ring and of a shape and size to fit into the groove aforesaid. After the mold is placed in position on the stool, the gasket is dropped therein between the mold and the pad and will fall in or adjacent to the open side of the groove. After this is done the gasket may be tamped into the groove by a tamping tool and the bottom of the mold is thus effectively sealed. This gasket may be of asbestos or other similar refractory and preferably flexible or com-

pressible material, and in order to maintain its shape it may be provided with a wire core on which asbestos rope or other similar refractory material may be wound, woven, or otherwise secured. If the material of the gasket is sufficiently stiff and has enough strength the gasket may be used without the wire core.

The refractory material which I prefer 10 to use is asbestos rope or other fibrous, pliant or flexible material, which is at the same time somewhat porous and contains air cavities so that it is easily compressible.

By compressible I mean material or materials which are capable of being compressed together or into a smaller space or volume, and this is true of my gasket by reason of the character of the materials used and the voids therein.

20 This is not true of the mud or slurry previously used, as these materials are not compressible and when put in place without pressure or with only a slight pressure they may change their form or shape by plastic 25 flow, but they are not compressible as above explained, as their volume is not decreased. Mud or slurry previously used is therefore not compressible in the sense of my invention, as my gasket is compressible by reduction 30 of its volume when placed or after it is in the groove, as herein described.

This gasket may be coated with graphite, talc, or other refractory and non-adherent material, either previously mixed with water 35 or other liquid to a creamy consistency or otherwise applied to the gasket in order to insure that it will strip from the ingot so that it may be used again.

My gasket is not friable and will not 40 break into pieces or produce spalls or fragments as will the dried mud or slurry previously used, but in order to be sure that no other foreign material that might cause defects in the ingot is in the mold, the mold 45 can be cleaned out by the use of an air suction pipe which is introduced therein, which withdraws any particles of sand, dust, dried mud, fragments of the sink head top lining or other loose material which 50 may have been deposited therein in any manner, so that the interior of my mold is absolutely clean and free from any foreign matter that would cause inclusions or defects in the ingot metal.

55 Although I have shown a gasket made of a one piece ring, or square with rounded corners, it may be composed of one or more pieces of asbestos rope or similar refractory, flexible and compressible material, overlapping or arranged in such a way as to fill the groove, but this is not as convenient as the continuous shaped gasket.

I have described my invention in connection with steel ingots, but it will be readily 65 understood that this is applicable to ingots

or other articles made of any metal whatsoever.

Having thus given a general description of my invention, I will now, in order to make the matter more clear, refer to the 70 annexed sheet of drawings, which forms part of this specification, and in which like character refer to like parts:

Figure 1 is a transverse sectional elevation through the intermediate portion of an 75 ingot mold, the sink head top and stool on which it rests, showing one form of apparatus used in connection with my invention. Figure 2 is a side view of one form of tamping bar which I may use to force the gasket 80 in place within the groove. Figure 3 is a cross section of the gaskets which are formed of asbestos or other material as previously described, wound, woven, or otherwise secured upon a core, which may be composed 85 of one or more wires as illustrated, but as above stated, I may not use wire cores if the gasket material is stiff and coherent enough and holds together sufficiently for placing in position. Figure 4 is a vertical sectional 90 elevation through the bottom of another slightly modified form of ingot mold and the stool upon which it rests. Figure 5 is a plan view of the gasket used to seal the groove in the bottom of the ingot mold illustrated in Figure 1. Figure 6 is to top plan view of one form of stool which may be used with the ingot mold illustrated in Figure 1. Figure 7 is a plan view of another form of stool used with the ingot mold of 100 Figure 4. Figure 8 is a plan of the gasket used with the ingot mold and stool illustrated in Figure 4. Figure 9 is another form of tamping tool which may be used for tamping the gasket into position at the base 105 of the ingot mold of Figure 1.

Referring now to the characters of reference on the drawings: 1 is an ingot mold illustrated in Figure 1; 2 are the top lifting lugs thereof, preferably made integral therewith; 3 are the bottom hold down lugs, but if this mold is used inverted they become the lifting lugs thereof; 4 is a staple projecting from the side of the mold for convenience in handling the same; 5 is the interior mold cavity of the ingot mold 1; 6 is a stool illustrated in Figures 1 and 6; 7 is a stool illustrated in Figures 4 and 7; 8 is the lower portion of the ingot mold cavity illustrated in Figure 4; 9 is the pad or projection on the stool 6; 10 are projections on the stool to assist in positioning the molds thereon and to insure that the groove between the ingot mold and the stool is of sufficiently uniform size throughout in order to receive 115 the gaskets 11 and 28, which are illustrated in Figures 1, 3, 4, 5 and 8. The casing for the sink head top is 12, the base flange thereof is 13, which may be provided with downwardly projecting lugs 14 in order to posi- 120 125 130

tion and center it on the top of the mold and this casing is provided with lifting lugs 15 preferably made integral therewith for the purpose of handling with a crane chain 5 or otherwise, while 16 is the upper flange of the sink head top casing, and the refractory lining of the sink head casing is 17. A metal suction pipe 18 is provided for the purpose of extracting or withdrawing from the mold 10 cavity any foreign material as heretofore mentioned, and this pipe is provided with a regulating valve 19 and the flexible suction hose 20, which is connected to any suitable source of vacuum or partial vacuum provided 15 with fan, syphon or other suction apparatus, not shown. As illustrated in Figures 2 and 4, 21 is a tamping bar which may be used for tamping the gaskets 11 and 28 in place after they have been dropped into or 20 placed adjacent to the groove between the bottom of the ingot mold and the edges of the stool pad, one end of the tamping bar 22 being curved as illustrated to correspond to the round corners of the groove between the 25 pad 9 and the ingot mold 1 or the curved groove of the mold 24, while the other end 23 is flat and narrow for use in the straight portions of the groove. As illustrated in Figure 4 this tamping bar is shown in dotted 30 lines in position for tamping the gasket 28 in the groove adjacent to the bottom of the ingot mold 24. The mold of Figure 4 is 24, and this is provided with an inwardly tapering lower end of concave and convex 35 form, the concave portion being 25 and the convex portion 26, the idea of this construction being to provide an ingot with a smaller end, which assists in preventing fins by reason of the quick chilling of the lower 40 portion of the ingot end due to its small mass as compared with that of the adjacent mold and stool. 27 is the pad on the stool 7, which is of circular form adapted to receive the gasket 28 between the edges of 45 said pad and the lower inner portion 26 of the ingot mold 24. As illustrated in Figure 3 the gasket 11 is provided with a single wire core 29, or it may be provided with a plurality of wires such as 30 twisted together 50 in the form of a cable. As previously stated these gaskets may, however, be made without a center or core.

As illustrated in Figure 9, 31 is a tamping bar formed with a rectangular portion 55 32 with rounded corners adapted to fit within the groove in the base of the ingot mold, so that the gasket 11 may be tamped therein by a few movements of the tamping bar instead of working more in detail as with the 60 tamping bar 21.

Having thus described my invention, what I claim and desire to secure by Letters Patent is:—

1. Apparatus for casting ingots comprising 65 an ingot mold, a stool on which said

mold is seated provided with a pad of lesser size than and extending upwardly into the mold bottom and a pliant and compressible gasket forced between the pad and the mold bottom to seal the same. 70

2. The combination of an ingot mold with a stool on which it is seated provided with a pad of lesser size than the mold bottom and extending upwardly therein, thereby forming a groove between the mold bottom and 75 the edges of said pad and a continuous gasket formed of compressible material inserted in said groove and compressed therein to seal the mold bottom.

3. The combination of an ingot mold with 80 a stool on which it is seated provided with a pad of lesser size than the mold bottom and extending upwardly therein, thereby forming a groove between the mold bottom and the edges of said pad, and a continuous ring 85 gasket provided with a metal core on which fibres of asbestos or similar compressible refractory material is mounted.

4. An ingot mold mounted on a stool provided with a pad or projection extending 90 upwardly for a short distance into the lower portion of the ingot mold, said pad being of lesser size than the mold bottom thereby forming a groove between the mold and said pad, a ring or continuous gasket formed of 95 fibrous or compressible refractory material provided with a stiff metallic core whereby it retains its shape, said gasket being forced into said groove to seal the mold bottom. 10

5. An ingot mold mounted on a stool provided with a pad or projection extending upwardly for a short distance into the lower portion of the ingot mold, said pad being of lesser size than the mold bottom thereby forming a groove between the mold and said 10 pad, a sink head top on the mold, a ring or continuous gasket formed of fibrous or compressible refractory material provided with a stiff metallic core whereby it retains its shape, said gasket being forced into said 11 groove to seal the mold bottom.

6. The method of making ingots consisting of mounting an ingot mold on a stool provided with a pad of size less than that of the interior of the mold bottom and projecting upwardly therein and forcing a gasket between the pad and the mold to seal the mold bottom, and then pouring metal into 11 said mold.

7. The method of making ingots which 12 consists in mounting an ingot mold on a stool provided with a pad of a size less than that of the interior of the mold bottom and projecting upwardly therein thereby forming a groove between said pad and mold bottom, then closing said groove by means of a gasket inserted in said groove to seal the mold bottom and then pouring metal into 12 said mold.

8. The method of making ingots consist- 13

ing of mounting an ingot mold on a stool provided with a pad of the general shape of the interior of the mold bottom but of less size, thereby forming an upwardly opening 5 space between said pad and mold bottom, then inserting a gasket in said groove to seal the mold bottom, placing a sink-head top on

the mold, then cleaning out the foreign material from the interior of said mold by suction and then pouring the metal into said 10 mold.

In witness whereof I hereunto affix my signature.

GEORGE E. THACKRAY.
